UNITED STATES PATENT OFFICE

163,259

CAMERA CASE

John E. Davis, Sherman Oaks, Calif., assignor to Revere Camera Company, Chicago, Ill., a corporation of Delaware

Application September 27, 1950, Serial No. 12,374

Term of patent 14 years

(Cl. D61—1)

To all whom it may concern:

Be it known that I, John E. Davis, a citizen of the United States, residing at Sherman Oaks, State of California, have invented a new, original, and ornamental Design for a Camera Case, of which the following is a specification, reference being had to the accompanying drawings, forming a part hereof.

Fig. 1 is a side elevation of a camera case, showing my design; the other side elevation being substantially identical thereto;

Fig. 2 is a front elevation thereof;

Fig. 3 is a top view thereof;

Fig. 4 is a rear elevation thereof; and

Fig. 5 is a bottom view thereof.

I claim:

The ornamental design for a camera case, as shown and described.

JOHN E. DAVIS.
